UNITED STATES PATENT OFFICE.

JAMES C. JOHNSTON, OF SCARBOROUGH, NEW YORK.

DESIGN FOR A CARPET-PATTERN.

Specification forming part of Design No. 5,427, dated December 19, 1871.

To all whom it may concern:

Be it known that I, JAMES C. JOHNSTON, of Scarborough, county of Westchester and State of New York, have invented a Design for Carpets, of which the following is a specification:

The nature of my design is fully represented in the accompanying photographic illustration, to which reference is made. It represents one-fourth section of said design, the other three-fourths being exact counterparts of the drawing.

What I claim, and desire to secure by Letters Patent, is—

The design for a carpet, as shown and described.

JAS. C. JOHNSTON.
